UNITED STATES PATENT OFFICE.

JACOB J. SMITH, OF PHILADELPHIA, PENNSYLVANIA.

IMPROVED BEDSTEAD-FASTENING.

Specification forming part of Letters Patent No. 42,120, dated March 29, 1864

To all whom it may concern:

Be it known that I, JACOB J. SMITH, of the city of Philadelphia, in the State of Pennsylvania, have invented a new and useful Improvement in Bedstead-Fastenings; and I do hereby declare that the following is a full, clear, and exact description of the construction and operation of the same, reference being had to the accompanying drawings, making a part of this specification, in which—

Figures 1 and 2 represent horizontal sections of a bedstead-post connected with the side and end rails by means of the said fastening; Figs. 3 and 4, sectional side views of parts of Fig. 1; and Figs. 5 and 6 perspective views of the two fastening-plates, (see connected in Fig. 1,) like letters, when in the different figures, indicating the same parts.

The nature of my invention consists, substantially as hereinafter described and specified, in the peculiar construction of two flat wrought-iron plates, and applying them to the post and rail pieces, respectively, of a bedstead, so that the plate in the one piece shall afford a slightly-inclined projection on one side only of an appropriate recess made in the said piece, and the plate in the other piece afford a bent projecting end, adapted to enter the recess in the first-mentioned piece and connect with the said inclined projection in the recess thereof, the two plates operating together, by the gravitation of the rail, to bind the latter and the post more firmly together, whereby a more simple, cheap, reliable, and durable fastening for bedsteads is produced.

In the drawings, A is the bed-post; B B', the rails; C C', the fastening-plates; D, the pins whereby the plates C are secured in the post and rail, respectively, and E the recess, which in the present instance is made in the post. The ends of the rails B B' are made without tenons. The post A has a recess, E, adapted to admit the projecting end of the plate C on its respective rail, which plate is simply a flat piece of wrought-iron having its outer end bent over to one side, so as to form an inclined face, f, on its inner side, and having also a hole, g, through its stem. One of such plates is driven sufficiently far into the end of the rail, and is there secured by means

of the transverse pin D, as seen in Figs. 1, 2, and 4.

In the post A, Fig. 2, a like plate, C, is driven in at one side of the recess E, until its outer end becomes flush with the outer surface of the post, and then secured therein by means of the pin D, as seen in the drawings.

In Figs. 1, 3, and 5 the plate C' is shown with an inclined half-dovetail, f', on its inner end, so that the said plate may serve the two-fold purpose of holding both rails, it extending from one recess to the other in the same post, as seen in Figs. 1 and 3. This latter mode of constructing and applying the recess-plate C' answers well in hard wood, but in the softer woods, or those of more indentable nature, the plate constructed and applied so as to require a distinct plate, C, for each recess, as seen in Fig. 2, is found to remain more firmly in its position, and is therefore preferable for the softer woods.

In the operation of this fastening it will be perceived that the plate C, when fixed in the recess E in either of the modes described, presents an inclined projection, f, only on one side of the latter, and receives thereon the inclined bent end or lateral projection f' of a like plate, C', fixed in the end of the rail, and, therefore, that the simple gravitation of the latter, when in juxtaposition with the former, will cause its end to be brought up into close and firm contact with the face of the post A, the length of the projecting part of the plate in the rail and the length of the recess E being such as to allow of the introduction of the said projecting part of the plate into such required connection with the plate in the said recess, and that this firmness of contact will result whether the said plates be constructed in either of the forms shown in Figs. 5 and 6. It will also be perceived that as it takes but about half the amount of the material and labor to produce these wrought-iron plate fastenings that are required to produce the cast-iron dovetail plug fastenings patented to me June 7, 1859, the cost of an efficient fastening for bedsteads is reduced by the present invention to nearly one-half that of the former; and what is of still greater importance, the present fastening, being made of wrought-iron,

it is not liable to be easily broken or put out of order in use, the latter being defects especially incident to all cast-iron fastenings.

Having thus fully described my improved fastening for bedsteads and pointed out its utility, what I claim as my invention, and desire to secure by Letters Patent, is—

The fastening described, the same consist-

ing of the plates C C', constructed and applied to the post and rails of a bedstead, so as to operate together in the manner described, for the purposes specified.

JACOB J. SMITH.
